CLAIM

I claim the ornamental design for a tow truck adapter, as shown and described.

DESCRIPTION

FIG. 1 is a perspective view of a tow truck adapter showing my new design;

FIG. 2 is a front elevation view thereof;

FIG. 3 is a back elevation thereof;

FIG. 4 is a left-side elevation view thereof;

FIG. 5 is a right-side elevation view thereof;

FIG. 6 is a top plan view thereof;

FIG. 7 is a bottom plan view thereof; and,

FIG. 8 is a perspective view thereof, showing the tow truck adapter in use.

The broken lines indicating a weld location, bolt, and a nut are included for the purpose of illustrating the unclaimed portions of the article and form no part of the claimed design.
